(57) CLAIM

We claim the ornamental design for a portion of a presser foot for a sewing machine, as shown and described.

DESCRIPTION

FIG. 1A is a perspective view of the presser foot for a sewing machine showing our new design;

FIG. 1B is an enlarged view of a section of FIG. 1A;

FIG. 2 is a front elevational view thereof;

FIG. 3 is a rear elevational view thereof;

FIG. 4 is a right side elevational view thereof, the left side elevational view being a mirror image;

FIG. 5 is a top plan view thereof; and,

FIG. 6 is a bottom plan view thereof.

The broken lines shown in the drawing disclosure are for illustrative purposes only and form no part of the claimed design.
